(57) **CLAIM**

The ornamental design for a panel, as shown and described.

DESCRIPTION

FIG. 1 is a perspective view of the panel, as seen from above and to the right;

FIG. 2 is a front view of the panel;

FIG. 3 is a left view of the panel;

FIG. 4 is a right view of the panel;

FIG. 5 is a bottom view of the panel; and,

FIG. 6 is a top view of the panel.

The phantom lines throughout the figures are included for the purpose of illustrating portions of the panel that form no part of the claimed design.
